UNITED STATES PATENT OFFICE.

JOHN THOMAS MARSH, OF FARMER CITY, ILLINOIS; LEWIS P. MARSH
ADMINISTRATOR OF SAID JOHN THOMAS MARSH, DECEASED.

GAGE-BOARD ATTACHMENT FOR SAWING-MACHINES.

SPECIFICATION forming part of Letters Patent No. 746,972, dated December 15, 1903.

Application filed April 7, 1903. Serial No. 151,515. (No model.)

To all whom it may concern:

Be it known that I, JOHN THOMAS MARSH, a citizen of the United States, residing at Farmer City, in the county of DeWitt and State of Illinois, have made certain new and useful Improvements in Gage-Board Attachments for Sawing-Machines, of which the following is a specification.

My present invention relates to an improved attachment for the tables or tops of sawing-machines for the purpose of supporting lumber at different angles to the saw.

A portion of my present invention is shown and described in my allowed application, Serial No. 129,280.

The invention is embodied in the means hereinafter described, and illustrated in the accompanying drawings, whereby a gage-board is adapted to be adjusted and supported at the various angles required.

In said drawings, Figure 1 is a perspective view illustrating my invention in connection with a lumber-carrier, to which reference will be hereinafter made. Figs. 2, 3, 3^a, and 4 are detail views of certain joints and connections, to which reference will be hereinafter made. Figs. 5 and 6 are respectively an end and plan view illustrating the adjustment of the gage-board.

Referring in the first instance to Fig. 1, A indicates the frame of my sawing-machine, and B a circular saw projecting through a slot in the table or top C, which is adapted to slide on the said frame A. In my aforementioned application this adaptation for endwise reciprocation of the table C is fully described and illustrated, together with improved roller-bearings for supporting the same and relieving friction.

E indicates a support or carrier for lumber, which may be employed in connection with the table-top and which is fully described and illustrated in my aforesaid allowed application.

D indicates the gage-board proper, in connection with which the lumber-carrier E may be employed at will—that is to say, the lumber-carrier is advantageously employed in connection with the gage-board; but it is to be understood that the latter is adapted for use independently thereof. The means for supporting and adjusting the gage-board at

different angles are as follows: Two rods or bars 1 are journaled in suitable holders or keepers 2, secured to the back of the gage-board at points midway between the centers and ends thereof. Clamps 3 are applied to the central portions of these rods 1, the same being formed of two plates arranged opposite each other and provided with a clamp-screw passing through them centrally. Rods 4 are arranged and held in the outer portions of said clamps 3, as shown in Figs. 1 and 4. It is apparent that by tightening or loosening the clamp the rods 4 may be adjusted as conditions require. The lower ends of the rods 4 are connected by right-angular rods 5 with horizontal rods 6, which slide in the eyes of clamp-bolts 7, the latter passing through the table, as shown in Fig. 1. By adjusting the nuts on the lower ends of the eyebolts 7 the rods 6 may be clamped in any adjustment to which they are adapted, so that they may be slid lengthwise or turned bodily to the right or left. The bent ends of the rods 5 are attached to the aforesaid rods 6 by means of a clamp 10, which is illustrated in Fig. 3. The same consists of an eyebolt having a nut 10^a, between which and the rod 6 a washer 10^b is interposed. By adjustment of the nut 10^a it is apparent that the clamp may be tightened or loosened, as conditions require, to provide for adjustments of the rods 5 on the rods 6. It is further apparent that this adjustment will be made when it is required to set the gage-board D forward or back on the table C relative to the saw B and also when the gage-board is to be set at a different horizontal inclination to the table, as illustrated in Fig. 6, where a piece of lumber X' is being sawed at an angle to its longer axis. The upper ends of the vertical rods 4 are adjustably connected with the bent rods 5 by means of diagonal rods 9, which are made in two parts connected by a rule-joint at 9^a. (See Fig. 1.) The lower or rear ends of said diagonal rods 9 are adjustably connected with the rods 5 by clamps 8, which are fully illustrated in Fig. 2. The clamp is formed of a U-shaped screw-bolt having nuts 8^a applied to its ends and a washer or plate 11 intervening the said nuts and the rod 5. It is apparent that by adjustment of the nuts 8^a the clamps may be slid along the rods 5, as re-

quired to permit adjustment of the gage-board D at different vertical angles, as illustrated in Fig. 5, where a piece of lumber X is shown supported upon the face of the gage-board at an angle to the table C and also to the saw B, which position provides for removal of the lower edge of the lumber, thus forming a bevel. The clamps 8 permit a certain adjustment of the gage-board in this manner; but to provide for a further or more extreme adjustment—that is to say, for placing the gage-board at a still greater inclination—the diagonal rods 9 may be bent upward at a greater or less angle by reason of the provision of the rule-joint 9^a, as illustrated in Fig. 3^a. It will be understood that when the jointed rods 9 are thus placed at an angle they will be held in such position by duly tightening the clamps 8 on the rods 9. In place of employing these means for holding the rods 9 at the required angle it is obvious that a suitable screw-clamp may be applied to the rule-joint 9^a.

Thus by means of the attachments provided between the gage-board D and the table C the former has a wide range of adjustment at different vertical and horizontal angles, and such adjustments may be made with great rapidity. Further, the said means hold the gage-board rigidly and constitute a very simple and cheap attachment.

Having thus described my invention, what I claim as new, and desire to secure by Letters Patent, is—

35 1. The combination with the slidable table and a gage-board resting thereon, of bent horizontal rods and diagonal rods having pivotal connection with the board adjacent to its top and bottom edges, clamps for securing the outer ends of the diagonal rods to the other rods, a third set of rods arranged parallel to the table and to which the aforesaid bent rods are secured and clamps applied to the table and in which the said third set of rods are slideable, substantially as shown and described.

40 2. The combination with the slidable table and a gage-board resting thereon of horizontal rods and diagonal rods having pivotal connec-

tion with the gage-board adjacent to its top and bottom edges, clamps for securing the outer ends of the diagonal rods to the other rods, and a third set of rods to which the aforesaid horizontal rods are secured, and clamps secured to the table and in which the said third set of rods are slideable, substantially as shown and described.

45 3. The combination, with the frame, the saw, and the table adapted to slide on said frame, of the gage-board resting upon the said table, vertical rods journaled on the back of said gage-board, and horizontal and diagonal rods pivotally connected at their inner ends with such vertical rods, and means for clamping the outer ends of said rods, substantially as set forth.

50 4. The combination, with the slideable table, and a gage-board adapted to be shifted to various horizontal angles, of the means for supporting the gage-board and permitting such adjustment, the same comprising rods which are journaled on the back of the board, parallel rods clamped on such journaled rods and adapted to swing horizontally, horizontal rods and diagonal rods attached to the upper and lower ends of the swinging rods, the said horizontal rods having an adjustable connection with the table, substantially as shown and described.

55 5. The combination with the table, a gage-board, and rods held transversely on the back of the latter, of jointed diagonal rods pivoted to such transverse rods, horizontal guides arranged parallel to the table, and clamps for securing the lower ends of such diagonal rods thereto, substantially as shown and described.

60 6. The combination with the table and gage-board, of jointed diagonal rods having a flexible connection with the gage-board, and means for securing the lower ends of such diagonal rods in different adjustments, substantially as shown and described.

JOHN THOMAS MARSH.
